UNITED STATES PATENT OFFICE.

FELIX E. LIETZ, OF BUFFALO, NEW YORK.

ROOFING CONSTRUCTION.

Application filed October 5, 1925. Serial No. 60,401.

To all whom it may concern:

Be it known that I, FELIX E. LIETZ, a citizen of the United States, residing at Buffalo, in the county of Erie and State of New York, have invented new and useful Improvements in Roofing Constructions, of which the following is a specification.

This invention relates generally to roofing or roof construction, but more particularly to improvements in the means employed for fastening flexible shingles in place on the roof.

Shingles of the class to which my invention is adaptable are laid diagonally and provided at their lower or free ends with flaps or turned-under corners.

One of the objects of the invention is to provide simple and inexpensive means for rigidly and reliably locking the flaps of such shingles in place so that they will effectually withstand the lifting action of high winds and driving rainstorms.

Other objects are to provide shingle-fastening means of this character which afford a material saving of time in the laying of the shingles, and which, while locking the corner-flaps in place, also serve to securely fasten adjacent or abutting underlying shingles to the roof boards, thereby eliminating the use of separate fastenings for this purpose.

In the accompanying drawings: Figure 1 is a fragmentary top plan view of a shingled roof embodying my invention. Figure 2 is an enlarged fragmentary top plan view thereof, partly in section. Figure 3 is a bottom plan view thereof, partly in section. Figure 4 is an enlarged transverse section on line 4-4, Fig. 1. Figure 5 is a vertical section on line 5-5, Fig. 1.

Similar characters of reference indicate corresponding parts throughout the several views.

10 indicates the usual roof boards or sheathing and 11 the customary starting strip of roofing material laid along the margin of the roof.

The shingles 12 are preferably constructed of prepared or composition roofing, such as felt saturated with asphalt and faced with crushed slate or other similar material, and are laid diagonally in the customary overlying courses, with the side corners of adjacent shingles partly cut away and abutting against each other, as shown in Figs. 1, 2 and 3. The lower or exposed outer corner

of each shingle has a turned-under flap 13 which is adapted to fit in the V-shaped space formed between the upwardly-converging edges of the two adjacent underlying shingles. This flap carries an upright locking tongue or extension 14, which is preferably constructed of a strong and stiff material such as galvanized iron, and which extends upwardly beyond the free end of the flap and is adapted to overlie the adjacent side corners of a pair of underlying shingles.

For the purpose of reliably holding or locking the corner flap of the shingle in place, a fastening device is provided which is preferably in the form of a U-shaped member or staple having a tie member or bar 15 arranged to extend over and across the butt joint between adjoining shingles, and prongs 16 depending from the ends of said tie-bar and constituting fasteners for securing the side corners of such adjoining shingles to the roof boards 10. The tongue 14 of the shingle is adapted for insertion between the tie-bar of the fastening device and the adjacent side corners of a pair of underlying shingles, as shown clearly in Figs. 2, 4 and 5. Being of a stiff material, this tongue is thus rigidly held beneath the staple to firmly lock the corner-flap 13 of the shingle down in place. The prongs 16 of the staple at the same time secure the side corners of adjacent shingles in place, thereby eliminating the use of separate fastenings for this purpose.

In order to facilitate the ready insertion of the locking tongue 14 beneath the tie-bar of the staple, the prongs 16 thereof are provided at their upper ends with downwardly-facing shoulders or stop flanges 17 which limit their downward movement or penetration, the shoulders being so disposed as to leave a space 18, between the underside of the tie bar and the upper sides of adjacent shingles, of such dimensions as to receive said locking tongue in the manner shown in Fig. 4.

As shown in Fig. 5, the tie-bar of the staple is preferably half-round in cross-section, the convex side facing downwardly for permitting the ready insertion of the locking tongue 14 into the space 18, and the flat side thereof facing upwardly and reducing to a minimum the resulting hump produced by the body of the shingle extending over the staple.

This improved device for locking the cor-

ner flaps of shingles in place and at the same time securing the side corners of underlying shingles to the roof boards, while manifestly simple and inexpensive in construction, permits of the expeditious laying of the shingles and produces a roof which is free from unsightly rivet heads or similar fastenings. Furthermore, it produces a rigid, strong and reliable lock for the exposed corners of the shingles, preventing their displacement by the lifting action of winds and driving rainstorms.

I claim as my invention:

In a roof construction, a plurality of shingles laid diagonally in overlying courses,

each shingle having a turned-under flap at its lower corner and a locking-extension carried by said flap, and a fastening device including a tie-bar extending across the side corners of adjacent shingles and terminating at its ends in depending prongs for securing such portions of the shingles to the roof, the prongs being provided near their upper ends with downwardly-facing shoulders, whereby a space is formed between said tie-bar and the adjacent portions of underlying shingles for receiving the locking-extension of an overlying shingle.

FELIX E. LIETZ.
